UNITED STATES PATENT OFFICE.

STACY B. HASELTINE, OF CHICAGO, ILLINOIS, ASSIGNOR, BY MESNE ASSIGNMENTS,
TO W. H. MINER, INC., A CORPORATION OF DELAWARE.

SHOCK-ABSORBING MECHANISM.

Application filed April 30, 1923. Serial No. 635,518.

To all whom it may concern:

Be it known that I, STACY B. HASELTINE, a citizen of the United States, residing at Chicago, in the county of Cook and State of Illinois, have invented a certain new and useful Improvement in Shock-Absorbing Mechanisms, of which the following is a full, clear, concise, and exact description, reference being had to the accompanying drawings, forming a part of this specification.

This invention relates to improvements in shock absorbing mechanisms.

One object of the invention is to provide a tandem shock absorbing mechanism, of simple, efficient, strong and durable construction, composed of few parts and capable of being cheaply manufactured, in which both cushioning units will be compressed under both buffing and draft strains, and in which the customary intermediate stops or shoulders on the side plates or stop castings may be dispensed with as well as the customary intermediate abutment block of the draw-bar yoke.

Another and more specific object of the invention is to provide a tandem shock absorbing mechanism, of the character indicated, wherein the front, rear, and intermediate follower elements are composed of a plurality of longitudinally arranged plates, the plates being arranged in two sets, one set co-acting with the rear end of the draw bar and the other with the rear end of the yoke.

Other objects and advantages of the invention will more clearly appear from the description and claims hereinafter following.

In the drawing forming a part of this specification, Fig. 1 is a vertical, longitudinal view of a portion of a railway draft rigging, taken along a line extending along the inner side of one of the draft sills, showing my improvements in connection therewith. Fig. 2 is a vertical, transverse, sectional view corresponding substantially to the line 2-2 of Fig. 1. And Fig. 3 is a plan view of one of the sections composing the rear follower. In said drawing, 10-10 denote channel shape center or draft sills of

the car underframe, each of said draft sills having a front stop lug 11 and a rear stop lug 12 secured to the inner face thereof. A portion of the draw-bar is indicated at 13, 55 and the same is operatively connected to an ordinary single pocket yoke indicated at 14 by means of a transversely arranged key 15 extending through the draft sills and working in alined slots therein, one of said slots 60 being indicated with dotted lines in Fig. 1. The shock absorbing mechanism proper is contained within the yoke 14 and all the parts are supported in operative position by a saddle plate indicated in 16. 65

The improved shock absorbing mechanism, proper, as shown, comprises, broadly, a sectional front follower A; a sectional rear follower B; and tandem arranged springs C and C'. 70

The sectional front follower A is composed of an upper plate-like section 17, a lower plate-like section 18 and an intermediate plate-like section 19. Each of the plate-like sections 17, 18 and 19 are of rectangular 75 shape, having flat front faces 20, 21, and 22, respectively, adapted to abut the rear face 23 of the drawbar 13. The upper and lower sections 17 and 18 are of like construction, being reversely arranged and, preferably, 80 duplicates. Each of the sections 17 and 18 is provided with an inwardly extending reduced arm 24, the arm 24 of the section 17 being upwardly offset with reference to the main portion of the section, thereby providing a shoulder 25, and the arm 24 of the lower section being downwardly offset with reference to the main portion of said section, thereby providing a corresponding shoulder 26. 85

The intermediate section 19 is provided with an inwardly extending arm 27 of reduced thickness offset with reference to the upper and lower surfaces of the main body portion 19 and centrally disposed, thereby 95 providing an upper shoulder 28 and a lower shoulder 29. The sections 17 and 18 are each provided with a pair of longitudinally arranged, spaced, concave recesses 30 and 31, the recesses 30 being provided with flat, 100 front and rear, end walls 32 and 33, respectively, and the recesses 31 being open at their

rear ends and provided with flat front end walls 34. The intermediate element 19 is also provided with a pair of longitudinally arranged openings 35 and 36; the openings 35 being provided with flat, front and rear, end walls 37 and 38 and longitudinally extending side walls, the latter being curved on their inner edges to correspond in curvature with the concave walls of the recesses 30. The opening 36 of the section 19 is open at the rear end thereof and has a flat front wall 39. As clearly shown in Fig. 1, the recesses 30 of the sections 17 and 18 and the opening 35 of the section 19 are in registration, having the front walls 32 and 37 in alinement and the rear walls 33 and 38 also in alinement, thereby providing a spring receiving chamber adapted to house the spring resistance C with the opposite ends thereof abutting the said front and rear walls. The opening 36 in the plate 19 is in registration with the recesses 31 of the upper and lower plates 17 and 18 and the wall 39 is in alinement with the walls 34 of the upper and lower elements 17 and 18 respectively, thereby providing a spring receiving chamber adapted to house the front end portion of the spring resistance C' with the front end thereof in abutment with the walls 34 and 39.

The sectional rear follower B consists of an upper section 40 and a lower section 41, the sections 40 and 41 being of like construction, preferably duplicates. Each of the sections 40 and 41 is provided with a longitudinal forwardly projecting extension, comprising a pair of arms 42 located at opposite sides thereof and connected by a transversely extending web 43 located between the body portion of the section and the outer ends of the arms 42. The arms 42 of the upper section 40 are so arranged as to extend between the rearwardly projecting arm 27 of the intermediate front follower section 19 and the arm 24 of the section 17, and the arms 42 of the lower section 41 are adapted to extend between the arm 27 of the section 19 and the arm 24 of the section 18. Both the upper and lower sections 40 and 41 are recessed as indicated at 44 thereby providing counterpart spring receiving openings having flat, rear end walls 45 and curved upper and lower walls corresponding in curvature approximately to the curvature of the outer coiled spring of the spring resistance C'. The longitudinal inner edges of the arms 42 are formed with transversely curved faces adapted to correspond with the curvature of the side walls of the recesses 44 and are in registration therewith. The web 43 connecting the arms 42 is formed with flat, front and rear faces forming abutment walls 46 and 47 respectively, adapted to coact with the rear end of the front spring resistance element C and the front

end of the rear spring resistance element C'.

As clearly shown in Fig. 2, the lower face of the body portion of the upper section 40 is provided with an offset portion 48, thereby providing a flat lower face 49, and a centrally located, vertical, longitudinally, extending shoulder 50, and the lower section 41 has the upper face thereof provided with an upwardly offset portion 51, thereby providing a flat upper face 52 and a vertical, longitudinally extending, centrally located shoulder 53. When the sections 40 and 41 are in assembled relation, the offsets 48 and 51 are adapted to inter-engage, with the shoulders 50 and 53 in abutting relation, thereby preventing relative lateral inward movement of the sections 40 and 41. In this connection it is pointed out that by providing the offsets 48 and 51, full vertical abutment shoulders 57 are provided and the sections 40 and 41 may be constructed as exact duplicates. The rear end faces 54 and 55 of the upper and lower sections 40 and 41 are adapted to abut the rear wall 56 of the yoke 14, and the walls 45, 46 and 47 of the upper section 40 are in alinement with the walls 45, 46 and 47 respectively, of the lower section, as clearly shown in Fig. 1.

When the mechanism is fully released, the parts assume the relative positions shown in Fig. 1, the front ends 20, 21 and 22 of the sections composing the front follower A abutting the front stop lugs 11 and the rear face of the drawbar, and the rear ends 54 and 55 of the sections composing the rear follower B abutting the rear stop lugs 12 and the rear wall 56 of the yoke 14, the walls 33 and 38 of the sectional front follower being in alinement with the walls 46 of the sectional rear follower, and the walls 34 and 39 of the sectional front follower being in alinement with the walls 47 of the sectional rear follower, thereby providing continuous abutments for the rear end of the spring resistance C and the front end of the spring resistance C', respectively.

The operation of the mechanism is as follows, assuming an inward or buffing movement of the drawbar. The sectional front follower A will be moved rearwardly with the drawbar, while the sectional rear follower B is held in fixed position by the rear stop lugs 12. The arms 24, and 27 of the front follower will slide rearwardly relatively to the interposed arms of the rear follower, thereby compressing the spring C between the front follower walls 32, 37 and the walls 46 on the webs 43 of the rear follower, and compressing the spring C' between the front follower walls 34, 39 and the rear follower walls 45. The relative sliding movement of the arms will continue until the shoulders 25, 26, 28, 29 and the rear ends of the arms of the sectional front follower A engage respectively, with the

front ends of the arms of the rear follower, and the shoulders 57 of the rear follower, thereby positively limiting the relative movement of the followers A and B before 5 the tandem springs become solid, and transmitting the force directly through the followers to the stop lugs of the draft sills.

During draft, the action is the reverse of that just described, the rear follower being moved forwardly and the front follower 10 being held stationary by engagement with the front stop lugs 11.

Upon the actuating pressure being relieved, the springs C and C' will act to 15 restore the front and rear followers to normal position, again bringing the walls thereof into alinement.

It will be evident that the sections composing the front and rear followers may 20 be very cheaply manufactured in the form of forgings or castings, and that the entire construction is exceedingly simple, especially since each section has only a single arm and only three different constructions 25 of sections are required, the section 17 being a duplicate of the section 18 and the section 40 being a duplicate of the section 41.

It will also be evident that an exceedingly rigid abutment is provided by the followers 30 when solid between the yoke and the draft lugs, the followers forming, in effect, a solid column or block, the only open space therein being that occupied by the springs.

I have herein shown and described what 35 I now consider the preferred manner of carrying out the invention, but the same is merely illustrative and I contemplate all changes and modifications that come within the scope of the claims appended hereto.

40 I claim:

1. In a tandem gear, the combination with a pair of pressure-transmitting elements, each of said elements comprising a plurality of longitudinally arranged sections, each of 45 said sections being provided with a longitudinally arranged arm and an abutment means, the arms associated with one of said elements extending between the arms associated with the other of said elements and 50 each of said arms having an abutment means near the free end thereof; of tandem arranged shock absorbing units, one of said units being interposed between the abutment means of the sections of one of said elements and the abutment means of said arms. 55

60 2. In a tandem gear, the combination with front and rear followers each composed of a plurality of abutting sections; of a plurality of inter-engaging pressure-transmitting elements, each of said elements being 65 formed integral with a section of one of said

followers and having intermediate follower acting means thereon; and tandem arranged shock absorbing units, one of said units being interposed between the front follower and the intermediate follower acting means, 70 and the remaining unit being interposed between the intermediate follower acting means and the rear follower.

3. In a tandem gear, the combination with front and rear sectional followers; of a plurality of inter-engaging pressure transmitting elements, each of said elements being formed integral with a section of one of 75 said followers and having intermediate follower acting means thereon; and tandem arranged springs, one of said springs being interposed between the front follower and the intermediate follower acting means, and the remaining spring being interposed 80 between the intermediate follower acting means and the rear follower.

4. In a tandem gear, the combination with front, rear and intermediate followers, each of said followers being composed of a plurality of sections, the sections composing 90 each of said front and rear followers being arranged in abutting relation, and the sections of one of said intermediate followers being alternate with and interposed between the sections of the other intermediate follower; of means for rigidly connecting the sections forming one of said intermediate followers with the sections forming the front follower; means for rigidly connecting the sections forming the remaining intermediate 95 follower and the sections forming the rear follower; and tandem arranged springs, said springs being interposed between the front follower and the intermediate followers and between the intermediate followers and the rear follower, respectively. 100

5. In a tandem gear, the combination with front, rear and intermediate followers, each of said followers being composed of a plurality of sections, the sections of one of said intermediate followers being alternated with and interposed between the sections of the other intermediate follower; of means for rigidly connecting the sections of one of said intermediate followers with the sections 110 forming the front follower; means for rigidly connecting the sections forming the remaining intermediate follower with the sections forming the rear follower; and tandem arranged spring units, said spring 115 units being interposed between the front follower and the intermediate followers and between the intermediate followers and the rear follower, respectively. 120

6. In a tandem gear, the combination with a plurality of longitudinally arranged, pressure-transmitting elements, each of said elements comprising a body portion and an arm extending therefrom, said elements being arranged in two sets, the arms of one 125

- set being alternated with and interposed between the arms of the other set, and the body portions of each set being in face to face contact; of abutment means on the body portion of each element; additional abutment means on each element on the arms thereof; and a spring resistance interposed between the first and second named abutment means of each set of elements.
10. 7. In a shock absorbing mechanism, the combination with front and rear followers, each of said followers comprising a plurality of separable, superimposed sections, each section of each follower having an arm extending therefrom toward the other follower, the arms of one follower being alternated with the arms of the other follower; of cushioning means between said followers.
8. In a tandem shock absorbing mechanism, the combination with front and rear followers, each follower comprising a plurality of separable sections, each section having an arm extending toward the other follower, said arms being alternated and provided with recesses so arranged that, when the mechanism is in assembled relation tandem arranged front and rear pockets are formed; of tandem arranged cushioning units, one disposed in each of said pockets.
30. 9. In a tandem shock absorbing mechanism, the combination with front and rear followers; each follower comprising a plurality of separable sections, each section having an arm extending toward the other follower, said arms being alternated and provided with recesses so arranged that, when

the mechanism is in assembled relation, tandem arranged front and rear pockets are formed; of tandem arranged cushioning units, one disposed in each of said pockets; and means for limiting the relative approach of said followers.

10. In a friction shock absorbing mechanism, the combination with front and rear followers; each follower comprising a plurality of separable sections, each section having an arm extending toward the other follower, said arms being alternated and provided with recesses so arranged that when the mechanism is in assembled relation a plurality of pockets are formed; of a plurality of cushioning units, one disposed in each of said pockets.

11. In a shock absorbing mechanism, the combination with front and rear followers having overlapping interengaging arms, provided with recesses so arranged that when the mechanism is in assembled relation, a plurality of pockets are formed, a plurality of said arms extending from each of said followers, each of said followers comprising separable sections, each of which is formed integral with one of said last named arms; of a plurality of cushioning units, one disposed in each of said pockets.

In witness that I claim the foregoing I have hereunto subscribed my name this 27th day of April, 1923.

STACY B. HASELTINE.
